FIG. 1.

Fig. 3.

A detailed technical line drawing of a mechanical assembly, possibly a pump or valve. The drawing shows a vertical column with a central shaft. At the top, a horizontal plate with a central hole is secured by a bolt (29). A vertical pipe (27) is attached to the side of the column. A circular component (28) is mounted on the shaft. The shaft is supported by a bearing housing (30) at the top and a base (10) at the bottom. A lever arm (5) is attached to the shaft, with a weight (3) hanging from its end. A rod (6) extends downwards from the shaft. A valve assembly (18) is located at the bottom, connected to a horizontal pipe (21). Other labeled parts include 1, 8, 9, 11, 12, 13, 14, 15, 16, 17, 20, 22, 23, 24, 25, 26, 28, 29, 31, and 32. The drawing uses fine lines and cross-hatching to indicate depth and material.

FIG. 5.

FIG. 5.

UNITED STATES PATENT OFFICE

WILLIAM NAGY, OF BETHLEHEM, PENNSYLVANIA

WATER-PUMPING DEVICE

Application filed February 28, 1927. Serial No. 171,627.

This invention relates to certain new and useful improvements in water pumping devices for the cooling systems of internal combustion engines.

5 The primary object of the invention is to provide a pumping device of the above kind which is extremely simple and durable in construction as well as efficient in operation, and which is so constructed and designed as 10 to reduce the liability of water leakage to a minimum.

A further object is to provide a pumping device of the above kind which may be readily applied to various types of engines 15 such as are now employed upon various makes of motor vehicles, and wherein simple and practical provision is made for operatively connecting the pump shaft to a driven part of the engine.

20 Still another object is to provide a pumping device of the above kind which may be cheaply and easily manufactured as well as readily placed into practical use.

Other objects will become apparent as the 25 nature of the invention is better understood, and the same consists in the novel form, combination and arrangement of parts hereinafter more fully described, shown in the accompanying drawings and claimed.

30 In the drawings, wherein like reference characters indicate corresponding parts throughout the several views,

Figure 1 is a top plan view of a pumping device constructed in accordance with the 35 present invention;

Figure 2 is a side elevational view thereof;

Figure 3 is a horizontal section taken substantially upon line 3-3 of Figure 2;

Figure 4 is a vertical section taken substantially upon line 4-4 of Figure 1;

Figure 5 is a side elevational view of the pumping device in operative relation to an 45 internal combustion engine and the parts of its cooling system, said engine and cooling system parts being indicated by dotted lines; and

Figure 6 is a transverse vertical section 50 taken substantially upon line 6-6 of Figure

5, showing the pumping device in front elevation.

Referring more in detail to the drawings, the present pumping device embodies a suitable supporting frame or bracket 5, preferably in the form of a vertical elongated plate, as shown, suitably re-inforced and adapted in any well known or preferred manner for rigid attachment to the engine with which the device is to be used. As shown, the supporting plate 5 tapers narrower in a downward direction by having one edge thereof vertical and the other edge of the same inclined, and rigid with the vertical edge of this plate as well as extending substantially from top to bottom of the latter is a tubular shaft housing 6. Rigid with the upper end of the plate 5 and housing 6 is a suitably shaped gear casing 7 having a water tight closure including a removable cover plate 8. Rigid with the lower end of the plate 5 and housing 6 is a horizontal pump casing 9 which may be formed in two parts or sections having a water tight joint and bolted together as shown at 10. The pump casing 9 is provided at its top side with an axial inlet from which extends a lateral horizontal nipple 11 disposed in a plane parallel with the plane of the plate 5 and adapted to facilitate connection of the bottom water outlet of a water cooling radiator 12 with the pump through the use of a hose or the like as at 13, in the usual general manner.

The pump further includes a rotatable 85 impeller 14 disposed in the casing 9 and fixed upon the adjacent lower end of a pump shaft 15 that is journaled in and extends through the shaft housing 6 and projects upwardly into the gear casing 7. Suitable bearings 16 and 17 for the pump shaft 15 are provided respectively at the lower end of the shaft housing 6 and the bottom of the pump casing 9, and means is provided for facilitating lubrication of these 90 bearings such as an oil or grease cup 18 carried by the housing 6 and associated with bearings 16, and an oil supply pipe 19 communicating with the interior of bearing 17. As shown, the lubricant is supplied to the 100

bearing 17 through an opening 20 in the pump casing 9, the pipe 19 extending from the opening 20 upwardly beside the engine to a convenient point near the top of the latter as best illustrated in Figures 5 and 6. Thus, oil or other lubricant introduced into the upper end of the tube 9 will be conveyed by the latter to the bearing 17 in an obvious manner. The pump casing 9 is further provided with a peripheral or tangential outlet nipple 21 adapted to be connected in the usual manner as at 22 with the inlet of the engine water jacket, the outlet of which jacket is connected in the usual way as at 23 to the top inlet of the radiator 12 as illustrated in Figure 5.

It will be understood that the manner of attaching the plate 5 to the engine must necessarily vary in accordance with the various makes of engines encountered, so that no uniform example of attachment can be relied upon. However, the selection of a suitable attaching means is well within the province of any skilled mechanic, and for this reason no particular attaching means is disclosed.

Suitably secured upon the projecting upper end of the pump shaft 15 within the bottom of the gear casing 7 is a bevel gear 24 meshing with a similar bevel gear 25 secured upon the adjacent end of a horizontal shaft 26 extending in a plane parallel with the plane of the supporting plate or bracket 5. The upper end of the plate or bracket 5 is formed with a pair of horizontally aligned bearings 27 and 28 in which the shaft 26 is journaled, and these bearings are equipped with suitable oil or grease cups as at 29, while the bearing 28 is rigid with the adjacent side of the gear casing 7 and has the adjacent end portion of the shaft 26 extending therethrough and projecting into the adjacent side of the gear casing 7 as shown clearly in Figure 4. Suitable means is provided upon the outer end of the shaft 26 for facilitating driving thereof from a suitable driven part of the engine. Obviously, this means will vary in accordance with different stages met with. In some instances, this means may necessitate the use of a sprocket wheel or spur gear fixed upon the end of the shaft 26, but as shown, it may embody a belt pulley 30 fixed upon said shaft and adapted to be driven by a belt 31 passing about a pulley 32 fixed upon an adjacent driven shaft 33 of the engine, such as an extension of the pump or cam shaft of said engine. In some instances, the belt will also pass about a pulley 34 of a shaft 35 carrying the usual air circulating fan 36 by means of which air is drawn rearwardly through the radiator 12.

In most instances, it will be found most convenient to mount the pumping device 65 within the engine hood beside the forward

side of the engine as illustrated in Figure 5 so that the nipple 11 projects forwardly and the nipple 21 projects rearwardly, while the shaft 26 extends forwardly from the gear casing 7 so as to present the pulley 30 in the same transverse vertical plane as the pulleys 32 and 34. With this arrangement it will simply be necessary to substitute a larger belt for the one formerly employed simply to pass about the pulleys 32 and 34, whereby the belt may also be passed about pulley 30 to communicate the drive of pulley 32 not only to the fan 36 but to the shaft 26 and, through the gearing described, to the pump impeller 14. With this arrangement of the device it will also be found very convenient to bolt the plate 5 to the engine. It is contemplated to pack the gear casing 7 with grease, and to replenish the supply of grease therein from time to time, the cover plate 8 may be formed with a filling opening closed by means of a removable plug 37.

An important feature of the present invention is illustrated clearly in Figure 5 wherein it is shown that the pump casing 9 is positioned in a plane below the bottom connection of the radiator 12, while the gear casing 7 will be disposed in a plane above the top of the engine. Thus, with a packing gland 38 provided for the bearing 28 leakage of water will be rendered quite unlikely because any water finding its way upwardly through the housing 6 will be resisted in outward passage to the bearing 28 by the grease or oil within the casing 7, and the packing gland 38 will not have to be able to resist a great pressure because when the water reaches this point its pressure will be greatly reduced substantially as experienced in the return connection 23 for the radiator 12.

From the above description it will be apparent that the present pumping device is of extremely simple and durable construction, comparatively leak proof, efficient and durable. It will also be appreciated that the device may be vended as an article of manufacture adapted for attachment to engines already in use with very little change or modification of the existing parts associated with the engine.

In operation, the driving of shaft 26 will be transmitted to the impeller 14, as stated, and the latter will cause the water to be drawn into the pump casing 9 through connection 13 and nipple 11 from the bottom outlet of the radiator 12. The impeller will further force this water out of the casing 9 through connection 22 into the water jacket of the engine, from whence the water will return by way of connection 23 to the top inlet of the radiator 12, thus completing the circle of circulation.

Minor changes may be made without de-

parting from the spirit and scope of the invention as claimed.

What I claim as new is:—

A casing structure for water pumping devices consisting of a single piece casting comprising a vertical shaft housing, a gear casing at the upper end thereof, a chamber at the lower end for the reception of a fluid impeller, a horizontal shaft bearing formed on the side of said gear casing, a web located in a vertical plane coincident with the axis of the vertical shaft housing and having at its upper end a shaft bearing, axially alined with the first named horizontal shaft bearing, the impeller chamber at the lower end of the vertical shaft housing having inlet and outlet connections for fluid circulation.

In testimony whereof I affix my signature.

WILLIAM NAGY.
